United States Patent Office.

AARON WARD, OF DUBLIN, INDIANA, ASSIGNOR TO HIMSELF AND JESSE HIATT, OF SAME PLACE.

Letters Patent No. 102,890, dated May 10, 1870.

IMPROVEMENT IN HARVESTER-DROPPERS.

The Schedule referred to in these Letters Patent and making part of the same.

I, AARON WARD, of Dublin, Wayne county, Indiana, have invented a new and useful Dropping-Attachment for Harvesters, of which the following is a specification.

Nature and Objects of the Invention.

This is an improvement in the class of grain-delivering mechanism of harvesters in which a shifting cradle or platform receives the grain as fast as it is cut and deposits the same in rear of or beyond the main frame, so as to be out of the way of the horses in the next through; and my invention comprises an arrangement of parts for performing these functions with less wear and tear and with more ease and regularity than heretofore.

General Description with Reference to Drawings.

Figure 1 is a perspective rear view representing my dropper in position for receiving the grain, the cut-off being elevated.

Figure 2 is a similar view, representing the same dropper in position for delivering the grain, the cut-off being depressed.

Figure 3 is a perspective front view of the operating gearing.

Figure 4 is a perspective view of the rack-driving spur-wheel with one of its bevel-pinnions.

Figure 5 is a top view of the segment-wheel with the cut-off treadle in section.

Figure 6 is a vertical section of the dropper in the line of delivery.

Figure 7 is a perspective rear view of the rack-driving spur-wheel.

All the figures, except the first, show the parts in the positions they severally assume at the instant of delivery, the first two figures being on a smaller scale than the others.

A represents a portion of the finger-bar provided with rearwardly-projecting hooked lugs, B, which support and guide a rack, C, whose rearwardly-projecting arms, D, support, about its mid-width, the tipping cradle E, jaws, d, on the ends of the arms compelling said cradle to travel with the rack from right to left and back again.

Also, extending rearward from the finger-bar, are arms, F, which support the left extremities of two bars, G, of rectangular transverse section, save at their notched triangular portions, g, and which, curving obliquely rearward from the outer end of the finger-bar for a short distance, as represented, extend thence leftward parallel with the finger-bar for a distance nearly equal to the stroke of the cradle.

The cradle E is provided beneath with two staples, H, which, encircling the bars G, serve, in conjunction with said bars, to guide and maintain the cradle

in its proper path, namely, at first to the rear and left, and, then, for the most part of its stroke, to the left simply, until reaching the outward termination of its stroke, and being no longer restrained by the rectangularity of the guiding-bar G, (in consequence of the staples H reaching the notches g,) the rear end of the cradle drops upon the ground, so as to deliver its load of grain.

On the cradle commencing its return stroke, the bevel of the notches g from left to right co-acts with the staples H to restore the cradle to its horizontal position, which position it retains at all times, except at the outward termination of its stroke, as aforesaid.

The rear portion of the cradle is composed of a series of fingers, e, whose weight preponderates over that of the front portion of the cradle sufficiently to insure the tipping action as above.

The rack C is reciprocated by spur-wheel I, whose shaft J is armed with a pair of similar bevel pinions, K, which, by meshing alternately with the segment L, on the front surface of the continuously-revolving wheel M, impart to the wheel I its said reciprocating action.

The wheel M may be driven by suitable geared connection, N, with the ground wheel.

On the rack C reaching either extremity of its stroke, a projection, o, from a spring, O, is caused by pin P or pin P', projecting from spur-wheel M, to enter an orifice, i or i', in the rack-driving wheel I, and thus prevent any accidental derangement or disturbance of the reciprocating parts during the operations of receiving and of depositing the grain.

Hinged to the finger-bar, or to projections therefrom, are two arms, Q, to whose free extremities are pivoted the handles or hafts R, R' of a cut-off board, W, which operates to temporarily catch and hold the grain while the cradle is out of the way.

One of the hafts, R, extends a short distance beyond the arm to which it is pivoted, so as to constitute the short end of a lever, and depending from this end is a treadle, S, which is confined in a guide, T, and terminates in a foot, U, which being at the proper juncture depressed by a projection, V, from the rear of the wheel M, operates to elevate the cut-off and to hold it in the elevated position while the cradle is in the condition for being charged with grain.

A notch, S, in the side of the treadle facilitates the escape of the latter from the action of the projection V, and insures a prompt return of the cut-off to its receiving position.

A shifting platform, or cradle, operated as above described, is believed to be far preferable to such as operate by swinging in the arc of a circle in the load-

ed condition, so as to strain the machine and disturb its balance, and by reason of their great weight to throw unnecessary labor on the team.

The rearward action by which the loaded cradle commences its stroke operates to disengage the butts of the grain from the sickle-bar.

My cradle, although here described as actuated by a rack, may obviously be reciprocated by a crank and pitman, or other equivalent device.

Claims.

I claim as new, and of my invention—

1. The tipping cradle E, reciprocated by rack O, or its equivalent, and guided by the notched and curved bars G g, first obliquely rearward and then sidewise,

and tipped at its point of delivery, substantially as set forth.

2. The combination of the tipping cradle E, cut-off R R' W, treadle S s U, and tappet V, substantially as set forth.

3. The combination of the cradle E, rack C, and reciprocating mechanism, substantially as set forth.

4. The projection P P', spring O o, and orifices i i', in the rack-driving wheel I, combined and operating substantially as and for the purpose set forth.

In testimony of which invention I hereunto set my hand.

Witnesses: AARON WARD.

GEO. H. KNIGHT,

JAMES H. LAYMAN.
